R. C. AIMONE

PHONOGRAPh CABINET

Filed March 22, 1922

INVENTOR

Raimondo C. Aimone

BY

Henry L. Lusk

ATTORNEY

UNITED STATES PATENT OFFICE.

RAIMONDO C. AIMONE, OF NEW ROCHELLE, NEW YORK, ASSIGNOR TO THOMAS A. EDISON, INCORPORATED, OF WEST ORANGE, NEW JERSEY, A CORPORATION OF NEW JERSEY.

DESIGN FOR A PHONOGRAPH CABINET.

Application filed March 22, 1922. Serial No. 1,336. Term of patent 14 years.

To all whom it may concern:

Be it known that I, RAIMONDO C. AIMONE, a citizen of the United States, residing at New Rochelle, in the county of Westchester and State of New York, have invented a new, original, and ornamental Design for Phonograph Cabinets, of which the following is a specification, reference being had to the accompanying drawing, forming a part thereof.

The figure is a perspective view of a phonograph cabinet showing my new design.

I claim:

The ornamental design for a phonograph cabinet as shown.

RAIMONDO C. AIMONE.
